UNITED STATES PATENT OFFICE.

SETH WILLIAM BABBITT, OF MERIDEN, CONNECTICUT.

DESIGN FOR A METAL ORNAMENT FOR SILVER OR PLATED WARE.

SPECIFICATION forming part of Design No. 35,998, dated August 12, 1902.

Application filed June 30, 1902. Serial No. 113,873. Term of patent 3½ years.

To all whom it may concern:

Be it known that I, SETH WILLIAM BABBITT, of Meriden, in the county of New Haven and State of Connecticut, have invented and produced a new, original, and ornamental Design for a Metal Ornament for Silver and Plated Ware; and I do hereby declare the following, when taken in connection with the accompanying drawings and the letters of reference marked thereon, to be a full, clear, and exact description of the same, and which said drawings constitute part of this specification, and represent, in—

Figure 1, a face view of a metal ornament for silver and plated ware embodying my design; Fig. 2, an edge view of the same.

This invention relates to an ornamental design for a metal ornament for silver and plated ware; and it consists in the configura-

tion as shown in the accompanying drawings. 20

As shown, the design consists of a full-blown narcissus A and a narcissus-bud B, their respective stems C D extending downward and united at their lower ends by a leaf E. 25

Having fully described my invention, what I claim as new, and desire to secure by Letters Patent, is—

The ornamental design for a metal ornament for silver and plated ware as herein shown and described. 30

In testimony whereof I have signed this specification in the presence of two subscribing witnesses.

SETH WILLIAM BABBITT.
